UNITED STATES PATENT OFFICE.

ARTHUR J. HODGE AND HENRY B. RUGGLES, OF PASADENA, CALIFORNIA, ASSIGNEES
TO AMERICAN PRODUCTS COMPANY, OF ST. LOUIS, MISSOURI.

HEAD FOR BARRELS AND THE LIKE.

1,268,460.

Specification of Letters Patent.

Patented June 4, 1918.

Application filed April 10, 1915. Serial No. 20,453.

To all whom it may concern:

Be it known that we, ARTHUR J. HODGE and HENRY B. RUGGLES, citizens of the United States of America, residing at Pasadena, in the county of Los Angeles and State of California, have invented certain new and useful Improvements in Heads for Barrels and the like, of which the following is a specification.

10 This invention has relation to certain new and useful improvements in heads for barrels and the like, and has for its primary object the provision of a form of removable head which may be readily placed in position and secured against movement.

The invention has for another object, the provision of a removable head of this character which may be readily secured in position in a barrel or the like of conventional 20 form and expanded and locked in position in such manner as to make it impossible for unauthorized parties to remove the head without being detected.

The invention has for still another object the provision of a head of this character formed of opposed substantially concavo-convex members, means for connecting and drawing together the centers of said members to force outwardly and tighten the 30 edges of the same against the interior of the barrel or other receptacle within which the head is positioned, and finally sealing means for covering and protecting the last mentioned means and thereby making it impossible to loosen or remove the head without first destroying the seal.

The invention has for a further object, the provision of a two-part head or cover of the above stated character which will be strong 40 and durable as well as flexible to a certain extent, and in which the upper or outer part of the head or cover will be corrugated radially to permit of ready expansion and outward movement of the outer or circular edge 45 of said part as the center of said part is drawn toward the center of the opposite or inner part of said head or cover.

The invention has for a still further object the provision of a head or cover of the 50 character described which will be of such form that the opposed and principal parts thereof may be readily formed of pulp or of any suitable and well known material and in which the seal or sealing member of the 55 cover or head will be of such form that the

tightening member of the head or cover will extend through the center of said seal or sealing member and the arms of the latter may be readily folded over one another above the head of the tightening member 60 and a rivet carried by one of said arms and extending through the registering aperture of the remaining arm may then be administered a blow sufficient to flatten the end of the same and thereby lock together the 65 arms of the seal or sealing member and prevent interference with the tightening member of the head or cover.

With these and other objects in view, the invention consists in the novel construction 70 and combination of parts as will be herein-after more in detail described, and the asserted novelty specifically pointed out in the claims.

In the accompanying drawings which 75 clearly and fully illustrate the invention:—

Figure 1 is a top plan view of the improved head resting loosely in the end of a barrel;

Fig. 2 is a vertical transverse section 80 through the same on the plane of line 2—2 of Fig. 1;

Fig. 3 is a view similar to Fig. 1 after the head has been tightened and the seal secured to prevent interference with the tightening 85 member of the head; and

Fig. 4 is a transverse vertical section on the plane of line 4—4 of Fig. 3.

Referring more particularly to the drawings in which similar reference characters 90 designate corresponding parts throughout the several views, 1 designates the upper portion of a barrel of conventional form having the usual croze 2 formed therein and upon the lower annular wall or shoulder 3 95 of which is placed our new and improved head or cover, it being understood that the shoulder 3 extends into the barrel toward the center of the same slightly farther than the upper shoulder or wall 4 of the croze 2, 100 thereby making it possible to readily place our form of head or cover upon said shoulder 3 with the circular edges or outer edges of the inner part 5 and outer part 6 of said head or cover directed toward the croze 2 105 and between the shoulders 3 and 4.

While the croze 2 is shown in the present instance as being produced by slightly decreasing the interior diameter of the barrel 1 immediately above and below the croze 110

and thereby forming the shoulders 3 and 4, the croze 2 may be produced and the shoulders 3 and 4 formed in any suitable and well known manner and this does not form a part 5 of the present invention. This present invention, however, resides in the head or cover which will now be specifically described.

The inner part 5 of the head or cover is 10 preferably formed of compressed pulp or fiber but may consist of any suitable material and is of substantially concavo-convex form and of the proper diameter to permit the circular or outer edge of said part 5 15 to rest loosely upon the lower shoulder 3 when the head or cover is positioned loosely in the barrel 1. The convex face of the part 5 is the lower face thereof and the internally threaded socket 7 is extended upwardly 20 through a central opening in said part 5 with a circular outwardly directed flange 8 carried by said socket 7 engaged against the under face or lower face of said part 5. The guiding and spacing collar 9 is secured 25 around the socket 7 and engaged against the upper face of the central portion of said part 5 and this collar 9 serves to retain the socket 7 in proper position. The collar 9 is provided in its upper face with a 30 flared central recess 10 which serves to guide the threaded head tightening member 11 to the upper end of the internally threaded socket 7 when assembling the parts 5 and 6 of said head.

35 The head tightening member 11 is preferably in the form of a screw having threaded engagement with the interior of the socket 7 and as this tightening member 11 extends through the center of the outer part 40 6 of the head, it will be evident that rotation of the same in one direction will serve to draw together the central portions of the parts 5 and 6 while rotation of the tightening member 11 in the reverse direction will 45 permit the central portions of the parts 5 and 6 to separate or move away from one another.

The head 12 of the tightening member 50 11 bears against the outer face of the seal or plate 13 which is secured to the outer face of the outer part 6 at the center of the same the member 11 being passed through an aperture in said plate 13 and as this plate 55 13 is preferably of metal or any suitable material, the head 12 of the tightening member 11 cannot pull through the same and through the outer part 6. It will therefore be seen that the central portion of the plate 13 serves as a reinforcement for the outer part 60 6.

The part 6 is also preferably formed of compressed pulp the same as the part 5 but may be formed of any suitable material. The part 6 is provided with radial corrugations, as will be readily seen by referring to 65

the drawings, and when the tightening member 11 is in normal position and the parts 5 and 6 separated for the purpose of placing the head in position or removing the same, the edges of the parts 5 and 6 are about even and the head or cover may be readily placed upon the lower shoulder 3 or raised from the same. As soon as the tightening member 11 is rotated in the proper direction, however, the central portions of the parts 5 and 6 will be drawn toward one another and the edges of said parts 5 and 6 will expand or move outwardly within the croze 2. Owing to the corrugations of the outer part 6, however, this part will give more readily than the part 5 and the outer edge of said part 6 will more readily move outwardly and spread within the croze 2 until it is tightly engaged against the vertical wall of said croze and the head or cover is thereby secured against movement or removal without first reversing the rotation of the tightening member 11. The relative positions and shapes of the parts 5 and 6 when the cover is secured in position may be readily seen by referring to Fig. 4 of the drawings.

After the head or cover has been securely fastened within the barrel or other receptacle, the oppositely directed radial arms 14 of the plate 13 are bent over the central portion of said plate and over the head 12 of the tightening member 11 and overlapped, as will be readily understood by referring to Figs. 3 and 4 of the drawings. One of the arms 14 has secured therein a rivet or sealing pin 15 which has only one end flat and the shank of said rivet or sealing pin is passed through the opening 16 provided for this purpose in the remaining arm 14 and as will be readily seen by referring to Fig. 4 the opening 16 and rivet or sealing pin 15 are directly above the tightening member 11 after said arms 14 have been properly folded over one another. The blow is then administered to the rivet or sealing pin 15 to flatten the opposite end of the same and thereby seal or lock the arms 14 in their folded or overlapped positions and prevent unauthorized parties from reaching the tightening nut 11 to rotate the same without first destroying the seal and thereby leaving evidence of their act. It will be readily understood, however, that after the proper parties have filed off one head of the rivet or sealing pin 15 and gained access to the contents of the barrel 1, the pin or rivet may be replaced and the cover or head for the barrel again used and properly sealed after being secured in position, thereby making it unnecessary to throw away the head or cover after only one use of the same.

While the preferred embodiment of the invention has been described and illustrated, various changes in the form, proportion and

minor details of the construction which fall within the scope of the appended claims, may be resorted to without departing from the spirit and scope of the invention or 5 sacrificing any of the advantages of the same.

What is claimed is:—

1. A removable receptacle closing head of convexo-convex form and composed of a pair of disks capable of being sprung inwardly and having their edges engaged and their central portions spaced apart, and means for drawing together the central portions of said disks to force outwardly the edges of the same and make a tight-closing joint therewith. 50
2. A receptacle closing head of convexo-convex form and composed of a pair of disks having their central portions spaced apart, a receiving member carried by one of said disks, the remaining disk being corrugated radially and capable of being sprung toward the other disk, and a tightening member carried by the last mentioned disk and telescoping with said receiving member to draw the last mentioned disk toward the first mentioned disk and spread the outer edge of said last mentioned disk to form a tight closure. 55
3. A head composed of a pair of disks having their edges engaged and their central portions separated, a receiving member carried by one of said disks, a tightening member carried by the remaining disk and engaged with said receiving member to draw the central portions of said disks toward one another and spreading the outer edge of said remaining disk, and means carried by the last mentioned disk for covering the end of said tightening member to prevent access to the same. 60
4. The combination with a receptacle having a croze formed therein with upper and lower shoulders; of a two-part hollow head positioned in said croze and resting upon said lower shoulder, means for connecting the central portions of the two parts of said head and drawing the same together to force outwardly the peripheral edges of said parts and move the same into binding engagement with the wall of the croze between said upper and lower shoulders, and a protecting and sealing means to prevent engagement of a tool with the first mentioned means to loosen and remove the head. 65
5. The combination with a receptacle having a croze formed therein; of a sectional hollow head loosely positioned in said croze, a tightening member for drawing together the sections of said head and forcing the outer edges of said sections into binding engagement with the wall of said croze to prevent movement or withdrawal of said head, a sealing plate carried by said head, said tightening member being extended through said plate, the ends of said plate being adapted to be folded over one another above the head of said tightening member, and a sealing rivet carried by one end of said plate and adapted to be secured through the remaining end of said plate to secure said ends in folded position. 70
6. The combination with a receptacle having a croze formed therein; of a head removably engaged in said croze, said head being hollow and having its upper half corrugated radially, tightening means for drawing the upper half of said head toward the lower half thereof and forcing the outer edge of the head into binding engagement with the wall of the croze, means for limiting movement of the upper half of said head toward the lower half thereof, and means for sealing the head in expanded position within said croze. 75

In testimony whereof we affix our signatures in presence of two witnesses.
